UNITED STATES PATENT OFFICE.

CARLETON A. ORR, OF PUEBLO, COLORADO, ASSIGNOR TO THE BAKER STEAM MOTOR CAR AND MANUFACTURING CO., INC., OF PUEBLO, COLORADO.

BOILER BLOW-OFF.

Application filed May 29, 1922. Serial No. 564,502.

To all whom it may concern:

Be it known that I, CARLETON A. ORR, a citizen of the United States, residing at Pueblo, in the county of Pueblo and State 5 of Colorado, have invented certain new and useful Improvements in Boiler Blow-Offs; and I do hereby declare the following to be a full, clear, and exact description of the invention, such as will enable others skilled 10 in the art to which it appertains to make and use the same.

The present invention relates generally to water boilers or steam generators, and aims to provide a novel and improved blow-off device for a boiler which enables the generating tubes or coils to be blown out individually or separately.

Another object of the invention is the provision of such a device including a slideable blow-off pipe or tube adapted to register in succession with the discharge ends of a series of generating tubes or pipes, whereby such tubes or pipes can be cleaned out in an efficient and convenient manner, 25 using the steam pressure or an external source of fluid.

With the foregoing and other objects in view, which will be apparent as the description proceeds, the invention resides in the 30 construction and arrangement of parts, as hereinafter described and claimed, it being understood that changes can be made within the scope of what is claimed, without departing from the spirit of the invention.

The invention is illustrated in the accompanying drawing, wherein—

Figure 1 is a vertical median section, portions being shown in elevation.

Fig. 2 is a section on the line 2—2 of Fig. 1.

The present improvements can be used in different types and constructions of boilers, and only that portion of the boiler in which the improvements are used is shown, 45 and the illustration is typical. The discharge terminals of the generating tubes or coils 4 enter a drum or chamber 5 in a longitudinal row or series, and, as shown, the terminals project slightly into the drum or chamber. The tubes or coils thus discharge 50 into the chamber, which has an outlet 6. In fact, the tubes 4 and chamber 5 can be arranged in different manners in various boilers, and the construction shown is for purpose of illustration.

In carrying out the invention, a blow-off tube or pipe 7 is slideable longitudinally within the drum or chamber, and passes through a stuffing box or packing 8 at one end of the chamber. The inner end portion 9 of the tube 11 is curved or bent toward the ends of the tubes 4, and has a terminal member or head 10 secured thereon provided with a port 11 to register with the discharge ends of the tubes 4. The member 10 bears 60 against the wall of the chamber or drum, and has a channel or groove 12 extending across the face thereof for receiving the projecting ends of said tubes 4, thus guiding the member 10 and terminal 9 of the tube 7 for 65 longitudinal movement along the ends of the generating tubes.

In order to hold the member 10 against the ends of the tubes 4, an arm 13 projects from the tube 7 opposite to the terminal 9, 70 and a roller 14 is mounted for rotation in the bifurcated end of the arm 13 to bear against the wall or side of the chamber or drum opposite to the member 10.

To facilitate the positioning of the tube 7 to register with the several generating tubes 4, a pointer 15 is carried by the chamber or drum 5 at the exterior thereof, and the tube 7 has numbered graduations 16 to register with said pointer, whereby the 85 member 10 may be brought into registration with the desired tube 4 by sliding the tube 7 to bring the corresponding graduation adjacent to the pointer 15.

Ordinarily, when the tube 7 is moved to 90 position the member 10 at the end of the chamber opposite to the stuffing box 8, all of the tubes 4 discharge into the chamber 5. In cleaning out the tubes 4, the tube 7 is slid to bring the member 10 into successive 95 registration with the discharge ends of the tubes 4, in order that said tubes can be blown-out one at a time. When the member 10 registers with one tube 4, and the discharge through the tube 7 is permitted, 100 said tube 7 being normally closed by a suitable valve or closure (not shown), the steam pressure in the boiler will force the steam and water through the corresponding tube 4 and out through the tube 7, thereby carrying the sediment, scale, and other foreign matter from the generating tube. The boiler pressure is thus used for cleaning out the tubes. However, when the boiler is idle, 105 the tubes can be cleaned out from the ex- 110

terior, by forcing steam, water or other fluid in through the tube 7 and through the tube 4 with which the member 10 registers. The boiler can thus be cleaned out 5 either from within or from without, and the tubes 4 can be blown out individually or separately, making the cleaning action more effective.

Having thus described the invention, what 10 is claimed as new is:

1. A blow-off device comprising a chamber, a plurality of tubes having terminals entering said chamber, and a blow-off tube movable in said chamber and having a member 15 at its inner terminal to register with said terminals of the first named tubes, said member having a portion slidably engaging the terminals of the first named tubes to guide said member for registration in succession with said terminals of the first named tubes.

2. A blow-off device comprising a chamber, a plurality of tubes entering said chamber, and a blow-off tube slidable in the cham-

ber and having a terminal member to register with the terminals of the first named tubes and provided with a channel to guide said member along said terminals. 25

3. A blow-off device comprising a chamber, a series of tubes having terminals entering said chamber in a row, a blow-off tube slidable in said chamber, a member on the inner terminal of the blow-off tube having a port to register with the terminals of the first named tubes in succession, said 30 member having a channel across its face to guide said member along said terminals of the first named tubes, and means carried by the blow-off tube to bear against the wall of the chamber to hold said member against 35 said terminals of the first named tubes. 40

In testimony whereof I have signed my name to this specification in the presence of two subscribing witnesses.

CARLETON A. ORR.
